UNITED STATES PATENT OFFICE.

WILLIAM TOWLER, OF LEEDS, ENGLAND.

COMPOUND TRAMWAY-RAIL.

SPECIFICATION forming part of Letters Patent No. 571,709, dated November 17, 1896.

Application filed August 31, 1896. Serial No. 604,429. (No model.)

To all whom it may concern:

Be it known that I, WILLIAM TOWLER, a subject of the Queen of Great Britain and Ireland, residing at Leeds, in the county of York, England, have invented an Improvement in Compound Tramway-Rails, of which the following is a specification.

My invention relates to compound tramway-rails in which the head or wearing part is formed separate and removable from the body of the rail, and more particularly to compound tramway-rails the body of which consists of a girder. The well-known advantages of compound tramway-rails have hitherto not secured for them a general use, owing to the fact that the means or method adopted for securing the head to the body have in a moderate time become defective or loose under ordinary working conditions; and it is the object of my present invention to provide for the attachment of the head to the body or girder portion in such a manner that the attachment will remain good and secure until the head has been worn out by traffic and requires to be replaced.

In the drawing, which represents a vertical cross-section of a rail embodying my invention, *a* designates the vertical flange, and *b* the head, of the girder. The sides of the head are vertical.

c is the separable or wearing head of the rail, which is provided on the under side with two side projecting flanges or rib *d*.

In order to firmly secure the wearing-head *c* to the girder-head *b*, I form the bottom of the head *b* on both sides *i* inclined slightly to the horizontal, a suitable inclination being from twenty to twenty-five degrees, though I do not limit myself to this exact inclination, and I bend or fold over the lower ends of the ribs or flanges *d*, after these have been pressed close to the sides of the head *b*, so that the

lower ends of the ribs or flanges *d* fit close and tight against the just-mentioned inclined under sides of the head *b*. This bending or 45 folding over may be effected by special clamp or rolling tools, but as the design of such may be varied and they form no part of my present application any description of such is omitted. For the same reason no description 50 of the tools for removing the rail-head *c*, when worn out, is added; but I propose to remove the head *c* either by wedging off the head or bending back, *i. e.*, outward, one of the ribs or flanges *d*, or cutting through the head at 55 the bottom of the wheel-flange groove *e*, or by cutting off one of the side flanges or ribs *d* level with the top of the head *b*.

I am aware that compound tramway-rails have been proposed or used in which the removable head has been provided with depending side flanges, with bolts or clamps passing through or from these securing the head to the body or girder of the rail, besides the use of such side flanges pressed against the 65 inclined sides of the head of a girder dove-tailed in section. I do not therefore claim such flanges broadly.

What I do claim as my invention, and desire to secure by Letters Patent, is—

The combination to form a compound tramway-rail of a girder having a head *b* approximately rectangular in section and with the under side *i* of the said head formed somewhat inclined to the horizontal with a separate removable head having depending side flanges or ribs *d* bent or folded close against the vertical sides and inclined under sides *i* of the girder-head substantially as described and illustrated.

WILLIAM TOWLER.
